DESIGN FOR A LAMP

Thomas Woodrow Wilson, Millville, N. J.

Application May 31, 1946, Serial No. 130,260

Term of patent 14 years

(Cl. D48—20)

To all whom it may concern:

Be it known that I, Thomas Woodrow Wilson, a citizen of the United States, residing at Millville, in the county of Cumberland and State of New Jersey, have invented a new, original, and ornamental Design for a Lamp, of which the following is a specification, reference being had to the accompanying drawing, forming a part thereof, in which

Figure 1 is a view showing a side elevation of the lamp showing my new design.

Figure 2 is a view showing a front elevation of the lamp.

Figure 3 is a plan view showing the underside of the lamp.

I claim:

The ornamental design for a lamp, as shown.

THOMAS WOODROW WILSON.
